CLAIM

The ornamental design for a handheld lint remover with cover, as shown and described.

DESCRIPTION

FIG. 1 is a top plan view of the handheld lint remover, shown separately for clarity of illustration.

FIG. 2 is a front elevation view of the handheld lint remover; the rear view being a mirror image thereof.

FIG. 3 is a bottom plan view of the handheld lint remover.

FIG. 4 is a perspective view of the handheld lint remover.

FIG. 5 is a left side elevation view of the handheld lint remover; the right side elevation view being a mirror image thereof.

FIG. 6 is a perspective view of the handheld lint remover, shown with a roller.

FIG. 7 is a front elevation view of the handheld lint remover, shown with a roller; the rear elevation view being a mirror image thereof.

FIG. 8 is a top plan view of the handheld lint remover in a closed position, inserted into the cover.

FIG. 9 is a front elevation view of the handheld lint remover in a closed position, inserted into the cover; the rear elevation view being a mirror image thereof.

FIG. 10 is a bottom plan view of the handheld lint remover in a closed position, with the handle inserted in the cover.

FIG. 11 is a perspective view of the handheld lint remover in a closed position, with the handle inserted in the cover.

FIG. 12 is a left side view of the handheld lint remover in a closed position, with the handle inserted in the cover; the right side view being a mirror image thereof.

FIG. 13 is a perspective view of the handheld lint remover with cover.

FIG. 14 is a front elevation view of the cover; the rear elevation view being a mirror image thereof; and,

FIG. 15 is a left side view of the cover; the right side view being a mirror image thereof.

The roller shown in broken lines is a feature of the article of manufacture that forms no part of the claimed design.
